[57] ABSTRACT

Apparatus for the draft and breaking of synthetic textile fibres which is designed to receive a fibre sliver coming out of a breaking machine and to complete the breaking of those fibres which have not yet been broken, characterized by the fact that the apparatus comprises a draft and breaking unit including a series of successive draft operations carried out at increasing speeds, a transfer unit for receiving the material from the draft and breaking unit and guiding it to a draft gill box for combing and drafting the material and, thereafter, passing it to a collecting device. The draft and breaking unit comprises at least two successive draft fields wherein the length of the first draft field is at least a third longer than the length of the next draft field. The combing operation of the draft gill box is performed by the mutual effect of two sets of vertical faller pins facing each other and operating from the lower and the upper part of the sliver and which are caused to gradually engage the sliver advancing in its traveling direction.

APPARATUS FOR THE DRAFT AND BREAKING OF SYNTHETIC TEXTILE FIBRES

The present invention relates to apparatus for the draft and breaking of synthetic textile fibres which are commonly named "technofibres" in order to perform the so called "tow to top" operative cycle.

The method of operating the apparatus of the present invention comprises the step of feeding the material coming out of a conventional breaking machine in the form of a sliver or tow, the step of subjecting said tow to a draft and breaking process comprising a series of draft operations to impart to the sliver increasing tensile stresses to cause the breaking of the continuous filaments which are still present in the sliver subsequently of the previous conventional breaking operation, and a draft and combing step to straighten the fibres by using a system of moving pins forming a gill box unit. This latter operation can be carried out by a gill box including two pluralities of parallel pins forming the fallers and which are actuated by faller screws or by an operatively equivalent device comprising rotating heads supporting the faller pins and which are driven by control and guide cams, such a draft and combing unit enabling operation at higher speed and with improved performances as compared with those of the conventional devices which are used in the art for the same purpose. In the conventional treatment of the synthetic fibres an apparatus is commonly used which comprises the following machines:

A breaking machine, a rebreaker, a draft and defelting machine and a draft and finishing machine.

The present invention provides an apparatus for carrying out the aforescribed operative method, which comprises a non-conventional combination of known devices enabling reduction of the duration of the operative cycle, the overall dimensions of the apparatus as well as a saving of labor, while obtaining a top having an improved fibre distribution and a better echelonment of the fibres of different lengths along said top.

The accompanying drawings show merely by way of indicative example, without limiting the invention, an embodiment of this latter; in said drawings:

FIGS. 1 and 2 show a diagrammatic longitudinal side view and a top view respectively of the apparatus of this invention;

FIG. 3 is the charge end view of the apparatus, taken on line X—X of FIG. 1;

FIGS. 4 and 5 are an enlarged detail of the side view of the draft and breaking unit of the apparatus, as shown in FIG. 1, and a cross section respectively, taken on line Y—Y of FIGS. 1 and 2;

FIG. 6 is an enlarged side view of the draft and breaking unit, of the transfer unit and of the combing unit partially broken away with details and particulars which cannot be seen in FIG. 1; and

FIG. 7 is a top view of the unit, wherein the sliver is transferred from the draft and breaking unit to the combing unit.

Now referring to the FIGS. 1, 2 and 3 it is to be noted that the present invention concerns in particular only the three operative zones of the apparatus which are marked A, B and C in FIGS. 1 and 2, while in the zone E there is provided a conventional feeding creel including a plurality of cylindrical cans 1 having vertical axes and open upper ends, said cans containing the material which is to be fed to the zone A by a belt conveyor 2 or other suitable device, and then to the zone B of the ap-

paratus, the operative cycle developing from the right to the left hand in the direction of the arrows, if reference is made to FIG. 1.

The most important unit of this apparatus is that operating in the zone A.

This unit comprises a plurality of groups, each including three cylinders; in the shown embodiment only three cylinder groups are provided. Said groups are arranged in series. Each draft and breaking cylinder 10 group comprises a upper cylinder 3 acting as a pressure cylinder, lined by anti-static rubber and two lower cylinders 4 made of steel and having grooved side surfaces. The pressure cylinders 3 are carried by self-aligning and self-centering bearings, and are associated with 15 means for adjusting their pressure.

The cylinders 3 and 4 of each operative group are each supported at both ends in order to obtain a wider work field and a higher and more uniform specific pressure on the sliver passing thereacross in transversal direction thus allowing a greater material charge without attaining remarkable elastic deformations. Said cylinders are caused to rotate about horizontal axes which are substantially perpendicular to the travel path of the material. The cylinders 4 of each group are driven by 20 drive means 14 (FIG. 6) which includes any suitable transmission means, not shown in the drawings.

In the zone A of the apparatus of the invention the fibre sliver or tow is subjected to a drafting and breaking action which is obtained by the drive means 14 25 causing the driving cylinders of the series of groups to rotate at different speeds, their speeds increasing in the travel direction of the material, i.e. from the right to the left hand according to FIGS. 1 and 2, so that the fibres which are longer than the spacing between two adjacent cylinder groups will be stressed to exceed their ultimate tensile stress.

Referring now to FIGS. 4 and 5, at least the two first groups of draft and breaking cylinders 3 and 4 are mounted on supports which can be displaced in the 40 travel direction of the material by sliding along the rails 13 in order to enable adjustment of their spacing so as to vary the fibrous diagram, that is to say, in order to vary the distribution of the textile filaments of variable length according to a stochastic gaussian law.

It is also to be noted that the operative characteristics of this apparatus, as compared with the conventional machines, permit treatment of a set of incoming slivers in a superposed relationship. As has hereinabove been 45 stated the draft and breaking unit A in the shown embodiment includes three cylinder groups A₁, A₂ and A₃ arranged in series as best seen in FIG. 6. The distance between the two first groups A₁ and A₂ is greater than 240 mm so as to obtain, in a very long draft field, i.e. a fibre drawing which may vary from 1 to 1.21 according 50 to the type of the treated material, in order to allow the fibres traveling along the draft field between the cylinder groups A₁ and A₂ to uniformly distribute the fibres in the longitudinal direction in particular in the case of long filaments so that these latter can be broken in the next draft field between the cylinder groups A₂ and A₃. The second draft field or distance between the cylinder groups A₂ and A₃ has a length which is less than that of the first one; it may be of about 160 mm, i.e. it is less by about a third of the length of the first draft field so as to 55 enable correction of the fibrous diagram of the sliver.

In this case the drawing effect can vary from 1.7 to 3.4 according to the type of the treated material; it is to be pointed out that the operative speeds of the cylinder

groups A_1 , A_2 and A_3 are gradually increasing so as to attain the breaking of all the longest filaments (> 180 mm).

After the sliver has exited from the zone A, said sliver enters the zone B comprising a section B_1 , where a guiding and transfer unit (FIG. 7) is provided comprising a conical guiding conduit $6a$ communicating with a substantially cylindrical conduit $6b$, at the outlet of which are arranged two dragging cylinders $6c$ and $6d$ having parallel axes and grooved side surfaces, the sliver which now has been transformed in a top being gripped between said cylinders $6c$ and $6d$ so as to be fed through the a draft gill box or field 5 placed in the zone marked B_2 and which is constituted of two pluralities of vertical faller pins $11a$, $11b$ respectively arranged in opposite directions, the lowering and lifting of which may be controlled by a screw system associated with guiding rails or by a rotating head system controlled by guiding cams.

The draft gill box or field 5 by means of the insertion of the pins in different positions and time relationship and the drafting effects obtained therewith, enables the regularization of the fibre distribution of the sliver so as to obtain a top having a uniform structure, a constant unit weight and which is ready to be fed to the next operative zone by means of the feeding cylinders $6e$, $6f$, and $6g$, at least one of which is a driving cylinder.

The following Table indicates the operative data obtained by using fallers for intersecting driven by control screws or by a head including rotating fallers the latter device being preferred since it permits an increase of the feeding speed of the sliver into the faller head from 16 to about 27.7 m/l with an incoming charge less than the 15%.

TABLE

Machine	Coupling	Gramm. top gr/mt	Feed charge gr/mt	Feed speed gr/mt	Predraft	Draft	Feed charge to fallers gr/mt	Feed speed to fallers gr/mt	Draft fallers	Output speed gr/mt	Output top weight gr/mt	Theor. product Kg/h	Efficiency %	End product Kg/h	
T3 With a faller head	12+	R= 28.4		620	5.5	1.09	2.67	213	16	9.7	155	22	200	80	160
With rotating head	11+	R= 28.4		560	8.9	1.1	2.88	180	17.7	7.2	200	25	300	80	240

The material coming out of the zone B is then passed in the zone C where a collecting device is arranged followed by a conventional discharge unit which collects the top into cans 7 or on bobbins.

The invention further utilizes two independent pneumatic cleaning devices, one operating in the draft and breaking unit A and the other being associated with the gill box 5, said devices being "per se" of any conventional structure and being actuated by the motors 9 and 10 respectively so that the operative cycle is improved since such independent pneumatic devices can be designed with different capacities, the device having the higher capacity is operated in the zone A, where the dust and fibre waste production is higher than in the zone B.

It is to be noted that by the use of the apparatus of this invention, the production is 60% higher than that obtained by the conventional apparatus.

I claim:

1. Apparatus for drafting and breaking synthetic textile fibres which remain unbroken subsequently of passage through a breaking machine comprising:

drafting and breaking means comprising a plurality of serially arranged drafting and breaking groups each group including an upper and two lower rotatable cylinders having parallel axes and arranged substantially perpendicularly to the direction of feeding of a fibre sliver therethrough, said upper cylinder comprising a pressure cylinder and having an elastically deformable substance on the exterior surface thereof, said lower cylinders comprising driving cylinders and having metallic grooves on the exterior surfaces thereof;

feed means for continuously feeding a previously broken fibre sliver to said drafting and breaking means;

driving means associated with said driving cylinders for rotating said driving cylinders of each of said drafting and breaking groups, said driving means including transmission means connected to said driving cylinders for transmitting motion from said driving means to said driving cylinders so that the speed of a successive drafting and breaking group is greater than the speed of the preceding drafting and breaking group;

draft faller means arranged subsequently of said drafting and breaking means for combing and drafting the fibre sliver;

transfer means for receiving the fibre sliver from the

last one of said drafting and breaking means and guiding it to said draft gill means, said transfer means comprising a first substantially conical guiding section and a second substantially cylindrical section; and

means arranged subsequently of said draft faller means for collecting the fibre sliver.

2. Apparatus according to claim 1, wherein the upper and lower cylinders of each of said drafting and breaking groups are each supported at both ends thereof and including means for supporting each drafting and breaking group in adjustable relation to one another in the direction of travel of the fibre sliver.

3. Apparatus according to claim 2, wherein the spacing between a first pair of said plurality of drafting and breaking groups is at least one third longer than the spacing between a second pair of said groups.
